UNITED STATES PATENT OFFICE.

LEO J. WERNER, OF ARLINGTON, NEW JERSEY, ASSIGNOR TO DUBILIER CONDENSER & RADIO CORPORATION, OF NEW YORK, N. Y., A CORPORATION OF DELAWARE.

CLAMPING DEVICE.

Application filed May 22, 1923. Serial No. 640,726.

To all whom it may concern:

Be it known that LEO J. WERNER, a citizen of the United States, residing at 134 Morgan Place, Arlington, in the county of Hudson and State of New Jersey, has invented certain new and useful Improvements in Clamping Devices, of which the following is a specification.

This invention relates to means for securing the knob and dial commonly used with electrical devices (particularly radio apparatus) to its associated shaft or spindle.

In such apparatus it is common practice to mount certain apparatus such as variometers and variable condensers upon a panel, and to adjust these devices by means of knobs positioned on the outside of the mounting panel. Such knobs commonly have associated with them a dial bearing 15 graduations or the like, whereby the adjustment of the associated devices may be observed.

Each of the devices adapted to be so adjusted is commonly provided with a shaft 20 or spindle on which the knob and dial are adapted to be secured. Various means are employed for securing the knob and dial to the shaft, and it is common practice to make the knob and dial integral and secure the same in position with set screws. When this is done, often the screws work loose or are inaccessible, or the heads of the screws are 25 so positioned as to be touched by the hand of the operator; this is objectionable, for several well-known reasons.

Another means of connecting the knob and dial is to provide a collapsible tubular socket adapted to tightly engage the shaft or spindle, this socket being forced inwardly 40 to grip the shaft by some suitable means such as a tapered nut. It is obvious, however, when such means is employed that there is a tendency for the dial to slip in the event the tapered nut becomes loose. Furthermore, it is difficult to initially put sufficient pressure on the tapered nut to cause the collapsible member to tightly grip the shaft.

The object of the present invention is to 45 provide means for rapidly and positively securing a knob and dial to an instrument shaft or spindle.

Another object is to provide an arrange-

ment whereby a firmer grip of the knob and dial upon the instrument shaft is possible 55 than heretofore.

A further object is to provide a means for attaching the knob and dial to a shaft that will not burr the latter and which requires no abnormal pressure or strain to be placed 60 upon the knob and dial when the same are being secured in position.

The accompanying drawings illustrate the invention.

Fig. 1 shows a face view of the knob and 65 dial members mounted upon their associated shaft.

Fig. 2 shows a knob and dial in central section mounted upon their associated shaft.

The numeral 1 denotes the shaft or spindle of any instrument which it is desired to 70 adjust or control. 2 is a dial and 3 a knob. 2 and 3 may be separate or made in one piece. For the sake of illustration, I show them as a single member made from moulded insulating material such as "bakelite" although they may be separate members secured together in any suitable manner.

The knob 3 is co-axial with the dial and extends beyond the forward face thereof. Secured in any suitable manner within this 75 forwardly projecting portion is the metallic member clamp 4 having a central aperture 5 adapted to receive shaft 1. At substantially right angles to said central aperture is a slot 6 which extends across the aperture 5 as shown in the drawing. The block 4 is almost cut in half by the slot 6, but hole 5 is in alignment in both portions thereof. The extent of the slot is shown by dotted line 10, 80 Fig. 1. The end 7 of the block 4 has a threaded hole 11 to receive the screw means 8 which passes through a hole in the other end of the clamp 4 as shown.

The knob 3 is provided with an aperture 9 which registers with the screw 8 whereby 85 the screw may be turned. That portion of the clamp 4 through which the body of the screw passes is bored out to accommodate same, so that the head of the screw, bearing 90 on the clamp, will draw the clamp together to close slot 6.

The complete assembly consisting of the 95 combination knob and dial, together with the metal member 4 secured thereto, (preferably by inserting the same in the knob and 100

dial when cast) may be placed upon the shaft, and secured tightly thereon by turning screw 8. The shaft 1 passing through both portions of the clamp is gripped between them at many points, as slot or recess 6 is closed. This pinching or binding action I find very effectual in securing the knob and dial in position on the shaft without burring or marking the latter. Furthermore, a relatively slight tension on the screw 8 securely clamps the parts in place, the clamping action being far more effective to hold the parts together than any set screw or collapsible tubular gripping arrangement. All metal parts being within or below the surface of the knob do not come in contact with the hands of the operator and therefore troubles from this source are eliminated. There is no strain on any of the moulded insulating parts, so trouble heretofore met

with from breakage of these parts is obviated.

I claim:

The combination of a knob, a clamp secured to the knob, said clamp comprising a pair of portions separated by a transverse recess, a bore in the clamp, a shaft received in said bore and extending across said recess, and screw means passing through one of the portions of the clamp, into engagement with the other portion to draw said portions towards each other and compel them to grip the shaft, thus securing the knob, the clamp and the shaft rigidly together, said knob having an aperture exposing said means to enable said means to be operated.

In testimony whereof he has affixed his signature.

LEO J. WERNER.
